R. WOOD.
COUNTER PRESSURE VALVE.
APPLICATION FILED MAY 20, 1915.

1,176,417.

Patented Mar. 21, 1916.

UNITED STATES PATENT OFFICE.

ROBERT WOOD, OF BROOKLYN, NEW YORK, ASSIGNOR TO THE NATHAN MANUFACTURING COMPANY, OF NEW YORK, N. Y., A CORPORATION OF NEW YORK.

COUNTER-PRESSURE VALVE.

1,176,417.

Specification of Letters Patent. Patented Mar. 21, 1916.

Application filed May 20, 1915. Serial No. 29,318.

To all whom it may concern:

Be it known that I, ROBERT WOOD, a subject of the King of Great Britain and Ireland, residing at Brooklyn, in the county of 5 Kings and State of New York, have invented certain new and useful Improvements in Counter-Pressure Valves, of which the following is a specification.

This invention relates to valves adapted 10 to control a conduit through which steam under high pressure is required to pass and under conditions where the control must be frequently exercised and the valve opened and shut many times to accomplish this purpose. A good example of the intended purpose is the steam starting valve on a locomotive where it is necessary to open and shut the valve frequently against a high pressure of steam. For such use, I have invented a 15 valve wherein the steam pressure assists in holding the valve upon its seat and at the same time exerts a counter pressure against the valve so that it can be manipulated without an unusual or undue exertion, and 20 the novelty of the device consists in the construction of the parts and the means employed to secure the proper performance of the stated function.

In the drawing, there is illustrated a 25 central longitudinal section of a valve and related parts embodying the invention. No other view is presented, because, as most of the parts are circular or tubular, a sectional view sufficiently displays the construction.

30 In the drawing, 10 is a valve casing provided on each side with a tubular extension 11 externally threaded to provide means for connecting it to the conduit through which the steam passes and which it controls. Ar- 35 ranged completely across the casing is a web or diaphragm 12 having a central opening indicated at 13 surrounded by an annular seat 14, and which casing is provided also with an inwardly extending annular 40 flange 15.

A bonnet 16 having an extending neck 17 externally threaded as indicated at 18 is secured to the casing by any suitable means as the screws 19. A valve stem 20 extends 45 through the bonnet and is loosely connected at its lower end by means of a transverse pin 21 with a valve disk 22 having an upwardly extending annular flange 23. At its upper end the stem is connected by a pivot 50 24 to a lever handle 25 pivoted at 26 to a

link 27 pivoted in turn at 28 to a ring 29 embracing the bonnet 16 and secured tightly against a shoulder 30 thereon by means of a retaining collar 31 engaging the threads 18. A stuffing box of usual form generally 55 indicated at 32 is secured to the bonnet neck 17 and packs the valve stem against leakage.

The valve proper comprises a disk 40 having a seating surface 41 coöperating with the seat 14. Below this is a piston 42 slidably engaging the flange 15 and connecting the disk and piston is a tubular member 43 having a side port 44. Above the disk 40 is an annular extension 45 of smaller external diameter than the internal diameter 60 of the bonnet so that there is an annular passageway 46 between them, and of greater internal diameter than the disk 22 so that there is an annular passageway 47 between them. Threaded into the upper part of the 65 extension 45 is an annular plug 48 between which and the valve stem is a passageway 49 and below which is a chamber 50 formed inside of the extension 45 and in which the disk 22 with its flange 23 has a limited vertical movement when the valve stem is reciprocated.

It will be noted that in the described construction there are shown in reality two valves, viz., a primary valve which is made 70 in the form of a cage consisting of the disk 40, the upwardly extending annular flange 45 and plug 48 and which cage is connected by the tubular stem 43 to the piston 42; and a secondary valve 22 which moves inside of 75 this cage and controls the passage of steam from the inlet side of the main valve down into the stem 43 and thence to the lower side of the piston 42, this valve acting upon a seat formed in the upper side of the disk 80 40 around the upper edge of the tube 43. Also that there is a leaking port 44 in such 85 passage. Also that the pin 21 forms a loose or hinged connection between the valve stem 90 20 and secondary valve 22 so as to allow the 95 valve to move properly even if the parts are 100 somewhat out of line.

The operation of the device is as follows: Assuming that steam is coming into the device from right to left, it will press upon 105 the annular edge of the valve disk 40 and help to hold its edge 41 against the valve seat 14; it will also pass up into the bonnet and down around the valve stem 20 and into chamber 50 and pressing on the upper 110

edge of the flange 23 will help to hold the valve disk 22 down upon the seat formed on the upper side of the disk 40 and shut it out from the passage into the interior of 5 the tube 43. Thus it will be seen the primary and secondary valves are both held closed by the steam pressure itself.

When it is desired to open the valve, the lever handle 25 is operated and the valve 10 stem 20 raised. This is not difficult to do because the area of the disk 22 is not very great, and the moment that it is lifted from its seat on the upper surface of the disk 40, the steam which is always present in the 15 chamber 50 passes into the tubular stem 43 and into the space beneath the piston 42 and helps by its pressure thereon to balance the pressure of the surface 41 against the surface 14, and by the time the movement 20 of the stem 20 has brought the upper edge of the flange 23 against the lower edge of the plug 48, which limits such movement, the counter pressure is such that the valve 40 is readily raised as the continued movement of the lever handle lifts the plug 48 and with it the remainder of the cage comprising the flange 45 and parts beneath. 25

The movement of the handle 25 in its opening operation should be gradual, so as 30 to allow a sufficient interval of time between the unseating of the auxiliary valve from its lower valve seat, to the seating of the same against the plug 48, thereby allowing a sufficient amount of fluid to pass to 35 the underside of the piston 42.

When it is desired to close the valve the handle 25 is moved to lower the stem 20, this moves the secondary valve downward and closing the passageway in the stem 43, 40 shuts off the steam acting upon the lower part of the piston 42. As soon as this is accomplished the valve 40 practically closes itself by the pressure upon its upper edge. It will be seen therefore that the primary 45 valve is not completely balanced. In fact, its efficiency depends upon the fact that it is not, but the moment the secondary valve is opened, the primary valve becomes balanced, at least to an extent sufficient to render its manual operation easy thereafter. 50

The port 44 is provided in case the secondary valve should leak. In such case, the steam coming down the stem 43 would naturally pass out through this port and would not exert a counter pressure upon 55 the piston 42. This port 44 is in direct communication at all times with the chamber or space beneath the piston 42 so that in the closing movement of the valve the steam in the space is allowed to escape, thereby 60 destroying the counter pressure therein.

I claim:

1. In a device of the character described, comprising a valve casing, a valve-seat therein, a valve for said seat, a piston connected to the lower side of the valve and a tubular extension on the upper side of the valve, said extension being provided with two valve seats, a cylinder in which said piston is adapted to reciprocate, a passageway connecting said tubular extension with the chamber in said piston cylinder, a valve in said extension arranged between the seats and adapted to close said passageway when moved to its limit of movement 70 in either direction and to permit fluid to flow to said piston chamber while in its intermediate position.

2. In a device of the character described, comprising a valve casing, a valve seat 80 therein, a valve for said seat, a piston connected to the lower side of the valve and a tubular extension on the upper side of the valve, said extension being provided with two valve seats, a cylinder in which said 85 piston is adapted to reciprocate, a passageway connecting said tubular extension with the chamber in said piston cylinder, a valve in said extension normally resting against one of the seats and adapted, when moved, 90 to first permit fluid to pass to said piston and chamber and then to close the passageway thereto when moved to the limit of its movement in the same direction.

In testimony whereof I affix my signature in presence of a witness.

ROBERT WOOD.

Witness:

MARY H. LEWIS.
